DESIGN FOR A FISH JAR

Michael S. Desser and Edwin W. Fuerst, Toledo, Ohio, assignors to Owens-Illinois Glass Company, Toledo, Ohio, a corporation of Ohio

Application November 10, 1936, Serial No. 65,818

Term of patent 14 years

To all whom it may concern:

Be it known that we, Michael S. Desser, a citizen of the United States, residing at Toledo, in the county of Lucas and State of Ohio, and Edwin W. Fuerst, a citizen of the United States, residing at Toledo, in the county of Lucas and State of Ohio, have invented a new, original, and ornamental Design for a Fish Jar, of which the following is a specification, reference being had to the accompanying drawing forming a part thereof.

In the drawing:

Fig. 1 is a side elevational view of a fish jar showing our design.

Fig. 2 is an end elevational view thereof.

Fig. 3 is a top plan view thereof.

We claim:

The ornamental design for a fish jar, substantially as shown.

MICHAEL S. DESSER.
EDWIN W. FUERST.
